(57) **CLAIM**

The ornamental design for a dial device, as shown and described.

DESCRIPTION

FIG. 1 is a front perspective view of a dial device showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown are included for the purpose of illustrating portions of the dial device that form no part of the claim.

1 Claim, 7 Drawing Sheets
